(57) **CLAIM**

The ornamental design for a barrier rail, as shown and described.

DESCRIPTION

FIG. 1 is a top and front perspective view of the barrier rail, showing our new design;

FIG. 2 is a right side elevation view thereof; the left side elevation view being a mirror image thereof;

FIG. 3 is an end view thereof;

FIG. 4 is a rear perspective view thereof; and,

FIG. 5 is a top plan view thereof.

The barrier rail is shown with a symbolic break in its length. The appearance of any portion of the barrier rail between the break lines forms no part of the claimed design.
